WEATHER STRIP

William J. Dennis, Chicago, Ill.

Application October 2, 1933, Serial No. 691,801

2 Claims. (Cl. 189—65)

- My invention belongs to that general class of devices known as weather stripping and relates to a metal weather stripping particularly designed for use on casement windows or the like which are designed to open outwardly. The type of strip herein shown and described is particularly adapted for use on casement windows provided with metal frames and sash to which the strip may be readily applied.
- The invention has among its objects the production of a device of the kind described that is simple, efficient, durable, inexpensive and which may be readily and inexpensively installed.
- The same also has as an object the production of a device of the kind described which may be installed without additional fastening means or with use of tools which may be made in a variety of sizes to fit different constructions, but which does not require exact size where there is slight variation in the dimensions of window frames of different windows or in the same window.
- Many other objects and advantages of the construction herein shown and described will be obvious to those skilled in the art from the disclosure herein given.
- To this end my invention consists in the novel construction, arrangement and combination of parts herein shown and described, and more particularly pointed out in the claims.
- In the drawing, wherein like reference characters indicate like or corresponding parts:
- Fig. 1 is a perspective view of a portion of the window frame and sash frame with the weather strip applied;
- Fig. 2 is a perspective view of a portion of a window frame showing application of the strip to the side of the frame; and
- Fig. 3 is a perspective view of a portion of a strip before application to the frame.
- Referring to the drawing, in which only one embodiment of the invention is shown, it may be mentioned that the window frame and sash frame illustrated in the drawing are typical of the usual construction, the frame being, of course, carried by the building structure and the sash being hinged to the window frame so as to swing in the desired direction.
- The weather strip is preferably made from sheet spring metal, such as spring bronze metal or the equivalent, which has resiliency and which will not corrode. The sheet of metal, which may be comparatively thin, is in the form of a strip of the desired width and length which is rolled, folded or bent to provide the strip proper and integrally formed means for securing the strip in place. In the strip illustrated the strip is formed with a portion 1 having one edge rolled over as indicated at 2 and thence bent as at 3 to provide a cooperating strip 4. The strip portions 1 and 4, as will be noted, are connected by a rolled over or intermediate portion without a sharp reverse bend so that the intermediate portion in a way constitutes a resilient hinge, the whole more or less resembling a V-shaped structure with the point of the V enlarged. The strip is secured in place by mounting the same upon the stop on the window frame so that the strip portions 1 and 4 are interposed between the stop and the window sash.
- As shown, the free edge of the strip portion 4 is folded back upon itself at 5 and extends as at 6 in proximity to the portion 4. The same is then bent laterally away from 4 as indicated at 7 to provide a portion 8 which extends substantially at a right angle to the part 6 and is adapted to seat upon the face of the stop frame. The extreme edge of the metal sheet is bent over as at 9 so as to provide the side portion 10 which is arranged to cooperate with portion 6 to form a stop clamp, whereby the weather strip is secured to the window stop and maintained in place without other fastening means. It will be seen by referring to Fig. 3 that the bend at 9 is sufficient to bring the extreme free edge of the portion 10 toward the portion 6 so that when the device is fitted to a window stop part 10 is under tension. It is generally preferred to form a bead or slight bend 11 at the juncture of the strip 1 and the intermediate portion 2 and to slightly turn over the edge 12 so as to provide a rolled edge where the strip first comes in contact with the window sash.
- Referring to Fig. 1, 15 represents the metal window frame which is provided with a window stop 16 and may be flanged as indicated at 17. The window frame also has the side frames formed as indicated at 18, 19 and 20. A typical sash frame is shown in Fig. 1 made up of the angle 23, 24 and 25 which is hinged or operatively secured to the window frame in any suitable or desired manner, usually hinged at one side of the window frame and provided with means at the opposite side for locking the same in closed position.
- The weather strip is applied to the frame of the window by seating the same on the flanges or stops 16 at the top and bottom and 19 at the sides. It is easily positioned by seating the member 10 and positioning the device over the stop with the side or end portion of the channel 8 seated upon 55

the face of the stop with the stop tightly clamped between the sides 6 and 10. When so arranged the tension or resiliency of the metal is sufficient to secure the strip in operative position and maintain it in that position. The stripping may be placed all around the window and ordinarily does not in any way interfere with the hinges or lock, it being obvious, however, that where necessary the same may be cut away to clear the window 10 hinges or lock wherever there is interference.

The resiliency of the metal tends to normally maintain the cooperating strips 1 and 4 as shown in the drawing. When, however, the sash is closed against the stop the strip portion 1 takes a position substantially as shown by the dotted lines in Fig. 1, contacting closely with the flange 24 of the sash and preventing the admission of air, dust or moisture between the sash and frame. When the window is open, the strip portion 1 immediately 20 springs out to substantially the position shown in the drawing.

It will be particularly noted that the rolled over portion 2 substantially overlies the portion 8 and does not engage or interfere with the closing of 25 the window. The advantage of having the rolled over portion rather than a sharp folding back or bent portion is obvious to those familiar with the working of metal of this kind. While there may be some relative movement of the parts 4 and 6 30 when the window is opened or closed, generally it is preferred to make the bend at 5 substantially as shown and to have the flexing or bending of the metal take part at the rolled over portion 2 where it is distributed over a considerable area. This 35 construction also permits the use of metal of a somewhat heavier gauge as the spring action is distributed and not localized. By forming the extreme edge 12 of the portion 1 with a slight roll or curve, obviously the window sash is not engaged 40 by a sharp raw edge which might stick or not ride over the face of the flange 24, especially if the same were rough or irregular in shape nor will it scrape the paint off. The stripping has plenty of 45 advantages, first, that it is extremely tight and efficient; secondly, that it is readily installed without supplemental fastening means or the use of tools; and third, that it is durable and of long life and is not unattractive in appearance. While 50 it is designed for windows opening outwardly it is not limited to such type of window.

Ordinarily I have found that it is sufficient to maintain the strip on the window frame solely by the frictional engagement or clamping of the frame by the portions 6 and 10, and ordinarily 55 this method of securing the same is preferred. In such instances, however, where it may be desired to lock the same by a positive engagement, this may be readily accomplished by providing a flange

29 on the portion 10 of the channel which will engage directly with the frame, either at the lower edge of the flange 16 or in a groove 30 (see Fig. 1) which may be formed in the frame. However, it is generally preferred to have the fit in the slot or at the bottom of the flange rather loose so as to allow for variation in frame sizes and location of the slot relative the top edge thereof so that the frictional engagement is effective and the positive engagement is only as a stop to limit accidental 10 displacement and prevent the strip from being pulled entirely off of the frame. Frictional engagement alone, however, as above mentioned, has so far proven satisfactory in use, but the positive engagement in some instances serves to satisfy the user as it appears to be more fixedly secured. 15

Having thus described my invention, it is obvious that various immaterial modifications may be made in the same without departing from the 20 spirit of my invention; hence I do not wish to be understood as limiting myself to the exact form, construction, arrangement and combination of parts herein shown and described, or uses mentioned. 25

What I claim as new and desire to secure by Letters Patent is:

1. A casement window weather stop of the kind described consisting of a sheet of spring metal rolled over lengthwise at a spaced distance from 30 one free edge to provide a cooperating strip, the free edge of the cooperating strip being bent back upon itself and thence laterally back and inwardly toward the cooperating strip to form a channel, the last mentioned extending part being operative 35 to frictionally engage a stop which is seated within the channel whereby the channel portion is retained on the stop.

2. A weatherstrip of the kind described consisting of a sheet of spring metal which is rolled over lengthwise to provide two cooperating strips connected by a rolled over intermediate portion, one strip adjacent its free edge being slightly bent toward the other and adjacent edge at the intermediate portion formed with a corrugation at the 45 juncture with the intermediate portion, the opposite opposed strip extending at its juncture with the intermediate portion toward the first mentioned strip and thence diverging therefrom with its free edge folded up and back upon itself in 50 close proximity thereto and thence bent away therefrom at substantially right angle thereto, thence bent back toward the said folded over portion and approaching thereto, the rolled over portion overlying the said right angle extending 55 portion.

WILLIAM J. DENNIS.
